[57] CLAIM

The ornamental design for a stopper with integral spraying device, as shown and described.

DESCRIPTION

FIG. 1 shows a front view of my new design with the rear view being a mirror image thereof;

FIG. 2 shows a left side elevation view thereof;

FIG. 3 shows a right side elevation view thereof;

FIG. 4 shows a top plan view thereof; and,

FIG. 5 shows a bottom view thereof.

The broken lines shown in FIG. 5 are for illustrative purposes only and form no part of the claimed design.
